(57) **CLAIM**

The ornamental design for an LED bulb, as shown and described.

DESCRIPTION

FIG. 1 is a top perspective view of an LED bulb showing my new design.

FIG. 2 is a bottom perspective view thereof.

FIG. 3 is a front view thereof.

FIG. 4 is a rear view thereof.

FIG. 5 is a left side view thereof.

FIG. 6 is a right side view thereof.

FIG. 7 is a top view thereof; and,

FIG. 8 is a bottom view thereof.

The broken lines in the figures depict portions of the LED bulb that form no part of the claimed design.
